RAZOR BLADE PACKAGE

Charles C. Baldwin, St. Louis, Mo.

Application November 10, 1938, Serial No. 239,775

3 Claims. (Cl. 206—46)

This invention relates to packages for merchandising various kinds of commodities and more particularly to razor blade packages, and to the mode and method of assembling a plurality of individually wrapped blades in such packages.

The principal object of the invention is to provide an improved form of razor blade package and a mode and method for assembling a plurality of individually wrapped razor blades arranged in superposed order and bound together in any suitable manner so as to be detachably united in book form, the individual blades of which package may be successively detached when desired without disturbing the intimate continuity or union of the remaining blades in the book, thereby preventing the unused blades from becoming separated, dislodged or lost in the process of handling the package.

A further object of the invention is to provide a package including a cover or retainer having a plurality of superposed individually wrapped or enveloped razor blades, which are detachably united by adhesive material applied to the confronting faces of their wrappers, secured thereto at the back thereof in book form, permitting the package to be flexed and the separation of the razor blades at their free edges to permit their convenient detachment from the retainer.

Another object of the invention is to provide a novel, attractive, convenient and inexpensive razor blade package, comprising a plurality of blades enfolded in individual wrappers and positioned in superposed order, and detachably connected to form a unitary package, the individual blades of which may be selectively or successively detached from the package without disturbing the remaining blades or their connections.

Another object of the invention is to provide an assembly of a plurality of blades positioned in superposed order, within individual wrappers or envelopes detachably connected, and permitting the selective or successive removal of the individual blades without the detachment or removal of the wrappers from the package.

With the foregoing objects and advantages in view, together with such other objects and advantages as may appear from the following specification, attention is directed to the accompanying drawings as illustrating certain preferred embodiments of the invention, and wherein,

Figure 1 is a perspective view of a closed package of razor blades assembled within a book-like cover and detachably united.

Figure 2 is a perspective view of the package shown in Figure 1, in open position showing the

blades in superposed order and in this instance attached by adhesive material positioned on the exterior of the opposed longitudinal overlapping portions of the outer blade wrappers at opposite ends to contact confronting faces of the said wrappers and the inner face of the back of the cover in the formation of the package.

Figure 3 is a perspective view of a package in general similar to that shown in Figures 1 and 2, except that in lieu of the book-like cover there shown, a single back or bottom portion of stiff paste-board or the like is provided for the attachment of the blade assembly.

Figure 4 is a perspective view of a modified form of cover or retainer having a back or bottom and two side portions, for housing the razor blades, which may be secured thereto in any suitable manner.

Figure 5 is a frontal elevation of a package showing a modified method of assembling a plurality of wrapped blades within a book-like cover, here shown opening endwise and the extended end portions of the superposed wrappers being attached to the comparatively narrow end portion of the cover by means of a staple or stitch.

Figure 6 is a perspective view of a package of similar mode showing the individually wrapped blades housed within the cover, the short encompassing end of which overlaps the extended end portion of the wrappers in attachment, by means of a staple or stitch passed through the said portions and clinched.

Figures 7 and 8 are perspective views of variant forms of package covers or retainers that may be adapted and used in conjunction with the invention.

Figure 9 is a plan view of a conventional razor blade wrapper in the open or unfolded position.

Figure 10 is a plan view of the conventional type of wrapper, shown in Figure 9, in the partially closed or folded position showing the adhesive material thereon.

Figure 11 is a plan view of a wrapper, in the unfolded position, formed so as to provide a short end flap for attachment to cover in assembly and an open upper end, when closed, thereby facilitating the removal of the blade therefrom.

Figure 12 is a plan view of the wrapper, as shown in Figure 11, in the closed or folded position.

In practicing this invention as exemplified in Figures 1, 2 and 3 the invention is shown as applied to safety razor blades 5 as conventionally inclosed in individual wrappers 6, the inner one of which is usually of moisture proof material

and the outer one providing space for suitable advertising matter in the formation of the package, the said wrappers each including a back portion 1 as indicated by the broken lines in Figures 9 and 11 of the drawings, upon which the blade is positioned, and side and end marginal folds or flaps 8 and 9, which are folded over inwardly upon the blade. In accordance with my invention, and in assembly, the outer 10 wrapper is preferably positioned on the blade by first folding the end flaps 9 inward upon the blade, and then the side marginal flap 8a, the same having suitable adhesive material positioned near the fold line at one end, is folded over inwardly, and likewise the opposite side marginal flap 8 is folded inwardly overlapping all the said flaps, and is held in closed position by contacting the adhesive material of the underlying flap 8a, the flap 8 having a somewhat larger 20 quantity of adhesive material 18a positioned also on its exterior face near the marginal edges of its free corner. A plurality of the blades thus inclosed each in its wrapper prepared with adhesive in manner described, are disposed one upon the other in superposed relation, and pressed together to form a connected book-like package.

Various forms of covers may be provided for the group of blades assembled and detachably connected as above pointed out. As shown in Figures 1 and 2 a book-like cover is provided, having front and back cover flaps 12 and 13. The assembly of wrapped blades is positioned within this cover by means of the adhesive material positioned on the exterior of flap 9 of the blade wrapper contacting the opposed inner face of the back flap 13 of the cover. Thus there is provided a convenient and neat package permitting the detachably united blades with free outer margins to be flexed like the pages of a book and the quick and easy detachment or selection of the blade when desired.

As represented in Figure 3 the book-like cover of Figures 1 and 2 is replaced by a single flap or piece of comparatively stiff paste-board 14 or the like, to which the similar assembly of wrapped blades 6 is attached in the same manner already pointed out.

In Figures 4, 7 and 8 are represented other forms of covers and retainers that may be used in conjunction with the wrapper and blade assemblies or packs already described. Figure 4 shows a form of retainer including a back 15 provided with perpendicularly turned side portions 16 within which the blade assembly is positioned and connected as described to the said back 15. Figure 7 shows a form of cover including a back 17, side portions 18, 19, front flap 20 hinged at 21 to the side portion 18, the side portion 19 having an inwardly turned lip 22, 60 and there being a cut-out 23 formed through this flange and lip to serve as a finger recess. In the use of this form of the cover, the assembly of the detachably connected wrapped blades as described, is mounted as aforesaid within this 65 cover, and the flap 22 is then closed down and if preferred adhesively attached to the lip 22. In opening this outer package, the user inserts a finger or thumb-nail through the recess or opening 23 and with a slight outward pull the 70 flap is free from the lip. In Figure 8 a retainer 24 is provided, the same having a side portion 25 and integral end portions 26, the assembly of wrapped blades being mounted therein in the manner already pointed out. Figure 9 shows a 75 conventional form of outer blade wrapper 6,

also comprising a central back portion 7, outer and inner side flaps 8 and 8a respectively, and end flaps 9, this being a form commonly used in the packaging of razor blades. Figure 10 represents this same conventional form of the outer wrapper as in process of use with the invention, showing the manner of locating the adhesive material 10 and 10a on the exterior of flaps 8 and 8a.

In Figures 11 and 12 is shown a modified form of the outer blade wrappers well adapted for use in conjunction with the forms of covers of Figures 5 and 6 of the drawings, the two side marginal folds or flaps 8 and 8a being shaped at their ends nearest the short end flap 9a to provide a convenient thumb-hold, when the wrapper is assembled, as shown in Figure 12 at 27, to permit the easy grasping of the blade in removing same from the wrapper or envelope either without detaching the said wrapper from the package or after detachment, if the wrapper is not detached from the package then same may be used to retain the used blades.

In the use of the forms of packages so far described and shown, the user merely opens the package as he would a book, by taking hold of the free edge of the uppermost exposed wrapper, and while holding the adjoining inclosed blade, and by an outward pull or separating action first detaches the closure flap from the underlying portion, since the greater quantity of adhesive material 18a, previously referred to, connecting the closure flap to the back of the adjoining wrapper prevents said flap from being readily detached, and permitting the blade in inner wrapper to be removed from the outer wrapper or envelope. If it is preferable however to detach the blade together with all its wrappers, then by a further pulling action upon the wrapper, the outer covering flap will be detached from the back portion of the contiguous wrapper to which it was adhesively joined, permitting complete removal from the pack. This operation of removal further results in spreading or pulling the flaps of the removed wrapper away from the inner wrapper and blade, thereby providing ready access for the fingers of the user for grasping same for the purpose of stripping the wrapper from the blade, thus facilitating this process. Meanwhile the remaining blades of the package are undisturbed and detachably united thereby preventing their separation and becoming loose to fall out and be lost or damaged.

In Figures 5 and 6 are shown other methods of connectedly mounting assemblies of wrapped blades within covers, and in Figures 11 and 12 are shown modified forms of outer blade wrappers well adapted for use in conjunction with the forms of covers of Figures 5 and 6.

In Figure 5 the cover, represented generally at 28 opens endwise instead of sidewise and includes the cover flaps 29-30 which are joined by a flexible integral end portion 31. One of the end flaps or folds 9 of the outer individual blade wrappers, which is represented at 6, is shortened as shown at 9a. These shortened flaps are positioned upon and attached to the end portion 31 of the cover by any suitable means. In this instance a wire staple 32 is forced through the end portion 31 and through the end flaps 9a, the ends of the staple being then bent down as shown. Thus the wrappers and inclosed blades may be handily detached as desired, without disturbing the remaining blades of the package.

Figure 6 exemplifies a form of package essentially similar to that of Figure 5, except that the

shortened flaps 9a of the blade wrappers are extended and positioned on the back portion 33 of the cover, where they are attached within the encompassing integral end fold 34 of the cover. 5 A wire staple 35 is then forced through the en-folding portions of the cover and flaps 9a as shown. Inclosing the free ends of the wrapped blades is the end portion 36 and the extended front closure flap 37 of the cover or retainer and by inserting the free end of the flap 37 under the free edge of the encompassing end fold 34 the package is held in closed position. 10

It will be noted that in all forms of the covers of retainers, and the outer individual blade wrappers herein shown and described that, the entire exterior of each may be used for the placement of suitable advertising material. And it will be seen that in all forms of the device herein described and shown there is provided a package 15 consisting of a plurality of individually wrapped razor blades detachably disposed in book-like formation and normally held against accidental displacement by suitable means, such as adhesive or staple or stitch and a cover or retainer for the 20 same; each form of the device being constructed so as to permit the successive detachment of the individual blades without disturbing the continuity of the package, and preventing separation or loss of the unused blades of the package. 25

While I have here shown and described certain preferred forms of the invention, it is understood that these forms may be varied in minor details, not departing however from the spirit of the invention as defined in the claims. 5

I claim:

1. A razor blade package of a plurality of individually wrapped and regularly superposed blades, inclosed in wrappers having marginal flaps folded over the blades, one end of the outer flap of each wrapper being attached to an inner flap of the same wrapper, and the opposite end being attached to the back of the contiguous wrapper. 15

2. In a package as defined in claim 1, the attachment between the contiguous wrappers being stronger than the attachment between the outer and inner flaps of each wrapper. 20

3. A razor blade package of a plurality of individually wrapped and regularly superposed blades, the wrapper of each blade including flaps turned inwardly over the blade, the wrapped blades being attached together in package form by means of adhesive between one of the flaps of one wrapper and the back of the contiguous wrapper. 25

CHARLES C. BALDWIN.
